DIELECTRICALLY TUNED WAVEMETER

Carl G. Sontheimer, Haddonfield, N. J., assignor
to Radio Corporation of America, a corporation
of Delaware

Application December 30, 1943, Serial No. 516,208

9 Claims. (Cl. 250—39)

1

This invention relates generally to microwave apparatus and more particularly to improved methods of and means for providing variable reactance and attenuation of microwaves in a waveguide transmission system.

One of the principal disadvantages of many types of conventional waveguide variable attenuators and tuning devices is that relatively movable metallic elements provide objectionable contact effects which cause undesired variations in the microwave current distribution in the waveguide conductors. Various types of movable metallic contact devices have been developed to minimize this effect by locating all movable mechanical contacts at points of minimum microwave current distribution. A necessity for such construction can be overcome by eliminating relatively movable metallic elements and substituting therefor relatively movable dielectric elements.

It is well known that microwaves may be attenuated by constricting the walls of a microwave waveguide transmission system to a dimension less than $\frac{1}{2}$ wavelength along the magnetic axis of wave propagation when the dielectric within the waveguide is air. For higher dielectric constant materials within the waveguide, the cutoff wavelength is increased in proportion to the square root of the value of the dielectric constant. The attenuation provided by waveguides constricted to less than the cutoff wavelength increases rapidly as the transmitted wavelength is increased above the critical value.

The instant invention utilizes this characteristic of waveguide transmission systems by employing a section of waveguide constricted to below the cutoff wavelength and coupled to adjacent waveguide sections providing free transmission of the microwaves. Variable attenuation is provided in the constricted waveguide portion by employing therein a combination of fixed and movable relatively high dielectric constant elements, proportioned and having dielectric constants such that free transmission of microwaves occurs only in such regions as are completely occupied by both the fixed and movable dielectric elements.

The ratio of the portion of the constricted waveguide employing only an air dielectric, or only the fixed dielectric, or only the movable dielectric, to that of the constricted waveguide portion entirely occupied by both fixed and movable dielectric elements, determines the effective reactance and attenuation of the constricted waveguide portion. The portion of the constrict-

2

ed waveguide entirely occupied by high dielectric constant material therefore will provide a transmission path having extremely low attenuation since the effective cutoff wavelength of this portion of the guide will be above that of the transmitted microwave energy. The resultant attenuation of the entirely constricted waveguide portion may be dependent upon the degree of penetration of the movable high dielectric constant material within the constricted waveguide portion.

The instant invention is an improvement upon the invention described in the copending application of Eugene O. Keizer, Ser. No. 507,467, filed October 23, 1943, upon which U. S. Patent 2,427,098 was granted on September 9, 1947, entitled "Variable attenuators for centimeter waves," and assigned to the same assignee as the instant application. One embodiment of the invention described in said copending application comprises a waveguide having a constricted portion connected, through a tapered waveguide portion, to a waveguide of conventional dimensions for the frequency to be transmitted. A tapered slug of high dielectric constant solid material may be moved longitudinally along the guide to vary the length of the constricted waveguide portion providing high microwave attenuation. A second embodiment of the invention described in said copending application comprises a constricted waveguide portion including means for introducing therein a high dielectric constant liquid. Various mechanical and hydraulic means are disclosed for actuating the high dielectric constant elements in the two embodiments.

Another invention related to the instant invention is disclosed in the copending U. S. application of Ernest G. Linder, Ser. No. 485,356, filed May 1, 1943, upon which U. S. Patent 2,423,396 was granted on July 1, 1947, entitled "Waveguide attenuators," and assigned to the same assignee as the instant application. The Linder application discloses various means for inserting energy absorptive dielectric elements within a waveguide to provide desired microwave attenuation.

The instant invention includes improved means for obtaining the desired attenuation of microwaves within a portion of a wave guide transmission system constricted to less than the cutoff wavelength, wherein a movable solid high constant dielectric element cooperates with a fixed high constant dielectric element within the constricted waveguide portion, to provide a variable length path of high microwave attenuation within the constricted waveguide portion.

The principle of the fixed and movable high constant, solid dielectrics within a constricted waveguide portion also may be applied to the measurement of microwave frequencies by incorporating this feature in a constricted waveguide which is loosely coupled to a conventional waveguide transmission system. Adjustment of the position of the movable solid dielectric element within the coupled constricted waveguide provides a section of the constricted waveguide which is resonant to the transmitted microwave energy, and hence which absorbs sufficient power from the transmission waveguide to provide an absorption indication upon a detector and indicator coupled to the transmission waveguide.

Among the objects of the invention are to provide an improved method of and means for attenuating microwave energy within a waveguide transmission system. Another object of the invention is to provide an improved method of and means for varying the reactance in a waveguide transmission system. A further object of the invention is to provide an improved method of and means for measuring the frequency of microwave energy transmitted through a waveguide transmission system. An additional object of the invention is to provide an improved method of and means for attenuating microwave energy in a waveguide transmission system by adjusting the relative positions of fixed and movable high constant solid dielectric elements within a portion of the waveguide system which is constricted to a dimension below the cutoff wavelength with a fluid dielectric.

The invention will be further described by reference to the accompanying drawing of which Figure 1 is a plan cross-sectional view of a waveguide employing one embodiment of the invention, Figure 2 is an end cross-sectional view of the embodiment of the invention shown in Figure 1, Figure 3(a) is an elevational cross-sectional view taken along the section line a—a of Fig. 3(b) of the wavemeter embodiment of the invention, Figure 3(b) is a cross-sectional plan view of said wavemeter embodiment taken along the section line b—b of Fig. 3(a), and Figure 4 is a plan cross-sectional view of a second variable attenuator embodiment of the invention. Similar reference characters are applied to similar elements throughout the drawing.

In Figures 1 and 2, microwaves introduced into region I of a rectangular waveguide transmission system 1, are considerably attenuated since the waveguide dimension along the magnetic waveguide axis a is considerably less than $\frac{1}{2}$ the wavelength of the transmitted microwaves. A fixed solid low-loss dielectric element 3 is disposed within the waveguide 1, and extends a predetermined distance L longitudinally along the guide. A second solid low-loss dielectric 5, proportioned to occupy the remainder of the interior of the waveguide 1 in the region adjacent the fixed solid dielectric element 3, is disposed within the guide and arranged to be longitudinally movable therein to vary the length of the region II wherein the guide is completely occupied by high dielectric constant material. In this region the waveguide is operated above the cutoff wavelength which is proportional to the square root of the dielectric constant of the inserted elements. The attenuation of region III of the constricted waveguide portion, which is occupied only by the movable solid dielectric element, provides additional attenuation which effectively is added to the attenuation by the region I, since both regions I and

III are operated above their cutoff wavelength. The amount of attenuation inserted in the waveguide transmission system may be indicated by means of a calibrated scale 7 disposed to cooperate with an indicator pointer 9 secured to the movable dielectric element 5.

In Figures 3(a) and 3(b) a conventional waveguide transmission system 11, having a cutoff wavelength above that of the longest wavelength transmitted microwave energy, is terminated in a microwave detector and indicator 13 of any conventional type. An aperture 15, in one of the wide faces of the transmission waveguide 11, opens into a short waveguide portion having its magnetic axis constricted to considerably less than $\frac{1}{2}$ the wavelength of the transmitted microwave energy. A fixed high constant solid dielectric element 17 occupies a portion of the cross-sectional area of the constricted waveguide portion adjacent the aperture 15 in the same manner that the fixed dielectric element 3 occupies a portion of the waveguide 1 of the device of Figure 1. Similarly, a movable solid high constant dielectric element 19, proportioned to occupy the remainder of the constricted waveguide portion 16 is movable longitudinally in the constricted waveguide, as described for the element 5 in the device of Figure 1. The regions I and III which are occupied only by one or the other dielectric elements, or by air, provide regions of relatively high microwave attenuation effectively to prevent leakage of microwave energy from the ends of the constricted waveguide portion 16. Region II, which is occupied by the overlapping portions of both the fixed and movable dielectric elements, provides a region of low microwave attenuation. If region II is adjusted to have a longitudinal dimension equal to any multiple of $\frac{1}{2}$ wavelength at the transmitted microwave frequency, this region will resonate to the transmitted energy, and absorb measurable power from the transmission waveguide system 11. The power thus absorbed will decrease the power delivered to the microwave indicator 13, thereby indicating resonance of region III to the transmitted energy. An indicator 21, secured to the movable solid dielectric element 19, and cooperating with a frequency or wavelength calibrated scale 23, may be employed to indicate the frequency or wavelength of the transmitted microwave energy transferred from the transmission waveguide system 11 to the waveguide 16. The indicator 21 may extend through a slot 25 in the upper face of the constricted waveguide portion 16. Leakage of microwave energy from the resonant portion of the constricted waveguide 16 may be minimized by locating the indicator 21 and scale 23 at the outer end of the movable dielectric element as shown in the device of Figure 1.

Figure 4 is another embodiment of the invention which provides a variable microwave attenuator having fixed and movable low-loss high constant dielectric elements within a portion of the waveguide transmission system which is constricted to considerably less than one-half the wavelength of the transmitted microwave energy. This embodiment of the invention permits the attenuation of the waveguide system to be varied from a relatively low value to a relatively high value. Microwave energy from a microwave generator, not shown, which is introduced into a conventional waveguide transmission system 31 operated above the cutoff wavelength, is introduced into a constricted waveguide portion 33 disposed normally to the waveguide 31.

A fixed low-loss, high constant dielectric element 35, occupying the full cross-sectional area of the constricted waveguide 33 for a portion of its length, and a fractional portion of the constricted waveguide portion for the balance of its length, is inserted within the constricted waveguide portion adjacent the generator waveguide 31. A movable low-loss, high constant dielectric element 37 is longitudinally adjustable within the constricted waveguide portion 33 to provide a region II which also is completely occupied by high constant, low-loss dielectric material. The portions of the constricted waveguide which are entirely occupied by the high constant dielectric elements provide regions of low microwave attenuation I, II.

The end portions of the constricted waveguide portion, indicated as regions III, IV, provide high microwave attenuation effectively to prevent leakage of microwave energy from the ends of the constricted waveguide 33. An output waveguide 39, similarly proportioned to the input waveguide 31, is coupled to the constricted waveguide portion 33 within the region II of low microwave attenuation. The resultant attenuation provided by the constricted waveguide portion 33, therefore, will be relatively low in the regions I and II and relatively high in the region V which is of adjustable length.

Since the movable dielectric element 37 may be inserted to any desired position within the constricted waveguide portion 33, it will be apparent that the region V may be made as short or as long as desired, and that the attenuation dependent thereon may be varied from relatively low to relatively high values. The movable dielectric element 37 may include an indicator 41 operated in cooperation with a fixed scale 43 to indicate the attenuation inserted in the waveguide transmission system for predetermined positions of the movable solid dielectric element 37.

Thus the invention disclosed comprises improved methods of and means for inserting variable reactance in a waveguide transmission system by means of relatively fixed and movable solid low-loss dielectric elements, thereby providing means for controlling the attenuation or for measuring the frequency of microwave energy in a waveguide transmission system.

I claim as my invention:

1. An adjustable microwave reactive device including a waveguide having a constricted portion providing a region of relatively high attenuation at the operating microwave frequency and mode of wave propagation with a low dielectric constant low-loss fluid occupying only a predetermined cross-sectional portion of said constricted portion, a fixed relatively higher dielectric constant low-loss solid element extending for a predetermined distance along the remaining cross-sectional portion of said constricted portion, means including a second microwave device coupled to said constricted waveguide portion for introducing microwave energy into said constricted waveguide portion, a movable relatively high constant dielectric low-loss solid element proportioned to occupy said predetermined cross-sectional portion of said constricted waveguide portion and means for adjusting the longitudinal position of said movable element in said constricted waveguide portion for effectively varying the reactance of said constricted waveguide portion and the microwave energy derived from said second microwave device.

2. An adjustable microwave attenuator includ-

ing a waveguide transmission system having a constricted portion thereof providing a region of relatively high attenuation at the operating microwave frequency and mode of wave propagation with a low-loss dielectric constant fluid occupying only a predetermined cross-sectional portion of said constricted waveguide portion, a fixed relatively higher dielectric constant low-loss solid element extending for a predetermined distance along the remaining cross-sectional portion of said constricted portion, means for introducing microwave energy into said constricted waveguide portion, means for deriving attenuated microwave energy from said constricted waveguide portion, a movable high constant low-loss dielectric solid element proportioned to occupy said predetermined cross-sectional portion of said constricted portion and means for adjusting the longitudinal position of said movable element in said constricted portion intermediate said microwave energy introducing means and said deriving means for adjusting said attenuation of said derived microwave energy.

3. An adjustable microwave attenuator including a rectangular waveguide transmission system having a constricted portion thereof providing a region of relatively high attenuation at the operating microwave frequency and mode of wave propagation with a low-loss dielectric constant fluid occupying only a predetermined rectangular cross-sectional portion having one dimension substantially coincidental with the electrical axis dimension of said constricted waveguide portion, a fixed relatively higher dielectric constant low-loss solid element extending for a predetermined distance along the remaining cross-sectional portion of said constricted portion, means for introducing microwave energy into said constricted waveguide portion, means for deriving attenuated microwave energy from said constricted waveguide portion, a movable high constant low-loss dielectric solid element proportioned to occupy said predetermined cross-sectional portion of said constricted portion and means for adjusting the longitudinal position of said movable element in said constricted portion intermediate said microwave energy introducing means and said deriving means for adjusting said attenuation of said derived microwave energy.

4. An adjustable microwave tuning device including a waveguide having a constricted portion providing a region of relatively high attenuation at the operating microwave frequency and mode of wave propagation with a low dielectric constant low-loss fluid occupying only a predetermined portion of said constricted portion, a fixed relatively higher dielectric constant low-loss solid element extending for a predetermined distance along the remaining cross-sectional portion of said constricted portion, means including a second microwave device coupled to said constricted waveguide portion for introducing microwave energy into said constricted waveguide portion, a movable relatively high constant dielectric low-loss solid element proportioned to occupy said cross-sectional portion of said constricted waveguide portion and means for adjusting the longitudinal position of said movable element in said constricted waveguide portion for effectively tuning said constricted waveguide portion and for controlling the microwave energy derived from said second microwave device.

5. An adjustable microwave tuning device includ-

stricted portion providing a region of relatively high attenuation at the operating microwave frequency and mode of wave propagation with a low dielectric constant low-loss fluid occupying only a predetermined rectangular cross-sectional portion having one dimension substantially coincidental with the electrical axis dimension of said constricted portion, a fixed relatively higher dielectric constant low-loss solid element extending for a predetermined distance along the remaining cross-sectional portion of said constricted portion, means including a second microwave device coupled to said constricted waveguide for introducing microwave energy into said constricted waveguide portion, a movable relatively high constant dielectric low-loss solid element proportioned to occupy said predetermined cross-sectional portion of said constricted waveguide portion and means for adjusting the longitudinal position of said movable element in said constricted portion for effectively tuning said constricted waveguide portion.

6. An adjustable microwave wavemeter device including a waveguide having a constricted portion providing a region of relatively high attenuation at the operating microwave frequency and mode of wave propagation with a low dielectric constant low-loss fluid occupying only a predetermined cross-sectional portion of said constricted portion, a fixed relatively higher dielectric constant low-loss solid element extending for a predetermined distance along the remaining cross-sectional portion of said constricted portion, means including a second microwave device coupled to said constricted waveguide portion for introducing microwave energy into said constricted waveguide portion, a movable relatively high constant dielectric low-loss solid element proportioned to occupy said predetermined cross-sectional portion of said constricted waveguide portion, means for adjusting the longitudinal position of said movable element in said constricted waveguide portion for effectively tuning said constricted waveguide portion, and an indicator coupled to said second device and responsive to said microwave energy for indicating the resonance of said tuned device to said operating frequency.

7. An adjustable microwave wavemeter device including a rectangular waveguide having a constricted portion providing a region of relatively high attenuation at the operating microwave frequency and mode of wave propagation with a low dielectric constant low-loss fluid occupying only a predetermined rectangular cross-sectional portion having one dimension substantially coincidental with the electrical axis dimension of said constricted portion, a fixed relatively higher dielectric constant low-loss solid element extending for a predetermined distance along the remaining cross-sectional portion of said constricted portion, means including a second microwave device coupled to said constricted waveguide portion for introducing microwave energy into said constricted waveguide portion, a movable relatively high constant dielectric low-loss solid element proportioned to occupy said predetermined cross-sectional portion of said constricted waveguide portion, means for adjusting the longitudinal position of said movable element

in said constricted waveguide portion for effectively tuning said constricted waveguide portion, and an indicator coupled to said second device and responsive to said microwave energy for indicating the resonance of said tuned device to said operating frequency.

8. An adjustable microwave wavemeter device including a waveguide having a constricted portion providing a region of relatively high attenuation at the operating microwave frequency and mode of wave propagation with a low dielectric constant low-loss fluid occupying only a predetermined cross-sectional portion of said constricted portion, a fixed relatively higher dielectric constant low-loss solid element extending for a predetermined distance along the remaining cross-sectional portion of said constricted portion, means including a second microwave device coupled to said constricted waveguide portion for introducing microwave energy into said constricted waveguide portion, a movable relatively high constant dielectric low-loss solid element proportioned to occupy said predetermined cross-sectional portion of said constricted waveguide portion, means for adjusting the longitudinal position of said movable element in said constricted waveguide portion for effectively tuning said constricted waveguide portion, and an indicator coupled to said movable dielectric element for indicating said tuning of said constricted waveguide portion.

9. An adjustable microwave wavemeter device including a rectangular waveguide having a constricted portion providing a region of relatively high attenuation at the operating microwave frequency and mode of wave propagation with a low dielectric constant low-loss fluid occupying only a predetermined rectangular cross-sectional portion having one dimension substantially coincidental with the electrical axis dimension of said constricted portion, a fixed relatively higher dielectric constant low-loss solid element extending for a predetermined distance along the remaining cross-sectional portion of said constricted portion, means including a second microwave device coupled to said constricted waveguide portion for introducing microwave energy into said constricted waveguide portion, a movable relatively high constant dielectric low-loss solid element proportioned to occupy said predetermined cross-sectional portion of said constricted waveguide portion, means for adjusting the longitudinal position of said movable element in said constricted waveguide portion for effectively tuning said constricted waveguide portion, and an indicator coupled to said second microwave device and responsive to said microwave energy for indicating the resonance of said tuned device to said operating frequency.
